COMBINATION BABY BATH AND DRESSING STAND

Shirley Daniels Chestine, 3500 Gibson Bldg. 402, Unit 961,
Detroit, Mich. 48201

Filed Oct. 28, 1970, Ser. No. 25,691

Term of patent 14 years

Int. Cl. D23—02

U.S. Cl. D23—52

FIG. 1 is a front perspective view of a combination baby bath and dressing stand showing my new design.

FIG. 2 is a rear elevation thereof.

FIG. 3 is a side elevation thereof.

FIG. 4 is a front elevation thereof.

FIG. 5 is a top plan view thereof, showing the dressing stand in its reversed position.

I claim:

The ornamental design for a combination baby bath and dressing stand, as shown.
